UNITED STATES PATENT OFFICE.

AUGUSTINE DAVIS, JR., OF COVINGTON, KENTUCKY.

MANHOLE.

1,329,040.

Specification of Letters Patent.

Patented Jan. 27, 1920.

Original application filed June 22, 1914, Serial No. 846,444. Divided and this application filed July 22, 1919. Serial No. 312,530.

To all whom it may concern:

Be it known that I, AUGUSTINE DAVIS, Jr., a citizen of the United States, and resident of Covington, in the county of Kenton and 5 State of Kentucky, have invented a new and useful Manhole, of which the following is a specification.

This application is a division of my application for oil wagon tanks, filed June 22, 10 1914, Serial No. 846,444. The object of the present invention is to provide an improved manhole for tanks; and the invention has to do with the formation of the manhole opening and the ring which receives 15 the screw cover, and with the manner of joining them, whereby a strong, light, leak-proof construction is obtained.

In the accompanying drawings forming a part hereof:

20 Figure 1 is a view partly in vertical section and partly in elevation of the manhole ring before being welded into the manhole opening of the shell;

25 Fig. 2 is a sectional view of the manhole portion of the shell flanged out to receive the ring; and

Fig. 3 is a sectional view of the completed structure.

The tank shell 1 is concavely flanged out 30 around the manhole opening 2, forming the tapered neck 7. The manhole ring 5 is inserted into the outer portion of the neck, and there secured by an oxyacetylene or like autogeneous weld 10, uniting thelapping portions at the edge of the neck. In 35 this way the parts are made practically as one; but if a simple ring were employed the results would not be satisfactory, since the thermal and contraction stresses would disrupt the internal screw 3 of the ring, so that 40 the manhole cover would not fit. This difficulty is overcome by providing a manhole ring having two differentiated portions, that is to say a relatively heavy or massive 45 outer or upper portion containing the screw-thread, and an inner or lower portion 9 which is unthreaded and tapered on the interior to a relatively thin edge, and by utilizing the latter portion to receive the 50 weld. As seen in Fig. 3 the screw collar of

the ring is outside of the neck and beyond the weld, while the portion 9 laps the edge of the neck, where the weld 10 is formed by fusing the edge to the side of the portion with addition of molten metal, the edge of 55 the portion 9 being left free.

Manholes constructed in this manner are light yet strong, relatively inexpensive to produce, and contain no joints through which liquid can escape or enter. The 60 flanged-out neck affords structural strength and furnishes a means of taking up contraction stresses and a region to which the ring can be successfully united and in which it is laterally supported. Furthermore, because of the ring being inserted into the neck, it is not necessary that the top of the latter be made square, it being sufficient merely to flange it out, with such incidental variation in level at different parts of the 65 rim as may occur. Setting the ring down into the neck also avoids an undue amount of projection.

While the invention has been described as a manhole, it will be understood that it 75 is equally applicable to other openings, and that the term, manhole, is used generically. A filler opening may be four inches in diameter as against fourteen inches for a manhole; but the construction for each is 80 identical.

What I claim as new is:

1. A manhole construction comprising a flanged-out neck on a tank or shell, a manhole ring inserted into the neck, said ring 85 having an outwardly projecting heavy threaded portion and an inner thin unthreaded portion lapping the edge of the neck, and an autogeneous weld uniting the parts at this region. 90

2. A manhole construction comprising a flanged-out tapered neck on a tank or shell, a manhole ring inserted into the neck, said ring having an outer screw portion and an inner plain portion lapping the edge of the 95 neck and tapered to a free thin edge within the neck, and an autogeneous weld uniting the edge of the neck and the side of the plain tapered portion of the ring.

AUGUSTINE DAVIS, JR.
